D. Knowlton,

Windlass.

N° 23,847.

Patented May 3, 1859.

UNITED STATES PATENT OFFICE.

DAVID KNOWLTON, OF CAMDEN, MAINE.

WINDLASS.

Specification of Letters Patent No. 23,847, dated May 3, 1859.

To all whom it may concern:

Be it known that I, DAVID KNOWLTON, of 5
Camden, in the county of Waldo and State
of Maine, have invented certain new and
useful Improvements in Windlasses and
Winches; and I do hereby declare that the
same are described and represented in the
following specifications and drawings.

To enable others skilled in the art to make
10 and use my improvements I will proceed to
describe their construction and operation
referring to the drawings in which the same
letters indicate like parts in each of the
figures.

15 Figure 1, is an elevation of my improved
windlass and winch. Fig. 2, is a plan or top
view of the same. Fig. 3, is an elevation of
one end.

20 The nature of my invention and improve-
ment consists in a winch shaft provided
with barrels and connected to the windlass
by gears so arranged that the windlass may
be worked by the winch shaft, or the winch
25 shaft and barrel may be worked independ-
ent of the windlass.

20 In the accompanying drawings A, repre-
sents a portion of the deck of a vessel, and
B, B, the windlass bitts, and C, the pawl
bitt; the whole being arranged in the usual
30 position. The windlass barrel D, may be
made in the form shown in the drawing, or
in such other form as may be preferred, and
fitted to turn in the bitts B, B, and pro-
35 vided with ratchet teeth E, for the pawl F,
which is hinged to the bitt C, so as to fall
into the ratchet teeth, and prevent the wind-
lass barrel from turning back. The winch
shaft G, is arranged parallel to the windlass
40 and above it, as shown in Fig. 1, and is
fitted to turn in the boxes H, H, fastened to
the windlass bitts, and in the box H', fast-
ened to the pawl bitt. The ends of the
45 shaft G, are made square to receive cranks
like the one shown at I, by which the shaft
may be turned to pull chains or ropes ap-
plied to the winch barrels J, J, which are
fastened to the shaft G, near each end.

50 The sockets K, K, are fitted to receive
hand spikes or levers to turn the winch,
either alone, or to operate the windlass as
may be desired. These sockets are arranged
to turn freely on the winch shaft G, and are
provided with pawls one of which is shown

by dotted lines at L, Fig. 3. These pawls
are arranged to catch the teeth of the ratchet 55
wheels M, M, when the sockets are moved in
the direction of the arrow to turn the shaft
G, and so as to slip over the teeth of the
wheels, when moved in the opposite direc-
tion. The ratchet wheels M, M, are firmly 60
fastened to the shaft G, and winch barrels
J, J, so as to turn them. The winch shaft G,
has the pinion N, fastened to it near the
pawl bitt C, which pinion turns the gear P,
fastened to the windlass barrel, to operate 65
it and haul in the cable. The shaft G, is
arranged to traverse endwise in its boxes,
so as to move the pinion N, in, and out of
gear endwise, by traversing the shaft G,
which has two collars Q, Q, fastened to it, 70
so that when the pinion N, is put in gear
with the gear P, it may be held there by the
latch R, and when it is put out of gear, it
may be held out, by the latch S; both of
which latches are fastened to the bitts B, B. 75

When the pinion N, is out of gear the
winch may be turned either by cranks or
hand spikes, or both, entirely independent of
the windlass which remains stationary. And
when it is desirable to use the windlass, the 80
pinion N, may be put into gear with the
gear wheel P, so as to turn the windlass
either by the winch cranks or hand spikes,
or both as may be desired, and according
to the power to be exerted.

85 By arranging the winch upon the wind-
lass bitts it is more out of the way, than if
it was applied to any other part of the
vessel; besides it costs far less to apply it
to the bitts than it would to erect standards 90
on purpose to support it. And by arrang-
ing it on the bitts above the windlass, it is
so near the windlass, that I am enabled to
connect the winch to the windlass, by a
pinion and gear wheel, thereby making a 95
geared windlass of great power, at a very
small expense. And at the same time have
a windlass that can be operated slowly with
great power by applying hand spikes to the
sockets; or operated quickly with less power 100
by turning the cranks: being admirably
adapted to get an anchor up quick, so as
to enable a vessel to escape squalls or bad
weather.

I believe I have described and represented 105
my improvements in windlass and winch so

as to enable any person skilled in the art to make and use them. I will now state what I desire to secure by Letters Patent to wit:

I claim the winch shaft G, provided with barrels J, J, and connected to the windlass by gears as described, and so arranged that the windlass may be worked by the winch

shaft, or the winch shaft and barrels, may be worked independent of the windlass, substantially as and for the purpose described. 10

DAVID KNOWLTON.
